MICROWAVE OSCILLATOR

Burton J. Udelson, Bethesda, Md., assignor to the United States of America as represented by the Secretary of the Army

Filed Jan. 13, 1965, Ser. No. 425,366
6 Claims. (Cl. 331—81)

The invention described herein may be manufactured and used by or for the Government of the United States of America for governmental purposes without the payment to me of any royalty thereon.

This invention relates generally to electron beam devices and more particularly to a D.C. pumped voltage tunable oscillator.

One of the more important advances made in the microwave art in recent years is the development of practical parametric devices. A parametric device may be generally considered to be a mechanism in which a particular output function is achieved through the periodic variation of system parameter. As applied to high frequency electron beam devices, the term generally refers to a device in which a variation in the electron beam is amplified through the periodic variations of certain electron beam or circuit parameters by means of a "pump."

An early successful embodiment of the principles of parametric amplification applied to an electron beam device, was the quadrupole amplifier. This amplifier includes an electron gun for emitting a stream of electrons, means for magnetically focusing the electron beam, an input coupler of the resonant or Cuccia type, a quadrupole interaction region, an output coupler, and a collector. While highly satisfactory for many applications, this type of parametric amplifier has several limitations. One of the chief limitations is that the pump energy, used to supply energy to the electron beam and produce amplification, must be twice the signal frequency. As the signal frequency increases, the disadvantage resulting from the requirement that the pump operate at a frequency twice the signal frequency becomes more and more acute.

To overcome this disadvantage, especially apparent at the higher signal frequencies, several electron beam parametric amplifiers with low pump frequencies or with D.C. pumps have been developed. D.C. pumped devices are characterized by having a D.C. pumped section which acts to increase a transverse displacement in the electron beam at the expense of decreasing the longitudinal velocity of the beam. All D. C. pumps may be classified into three basic types depending upon the wave interaction that takes place. The three types of wave interaction are: coupling between a fast and a slow cyclotron wave; coupling means a fast or slow cyclotron wave and a synchronous wave; and coupling between two synchronous waves.

These different types of D.C. pumps may be distinguished by reference to the general formula for the condition of D.C. pumping:

$$2L = n\lambda$$

where n is an integer, L is the spacial periodicity of the change of any of the parameters of the system, and λ is the wavelength due to the natural resonant frequency of the system. Coupling between a fast and a slow cyclotron wave is characterized by $n=1$. Coupling between a fast or slow cyclotron wave and a synchronous wave is characterized by $n=2$. Coupling between the synchronous waves is a special case of $n=1$ when both L and λ are equal to infinity.

Several prior art devices have made use of these D.C. pumping principles. Usually the required natural resonance of the system is the cyclotron resonance due to the longitudinal magnetic focusing field, and spacial periodicity is achieved either by varying periodically the voltage

2

along the length of the pumping section or by varying periodically the strength of the magnetic field. While such devices have obviated the need for higher pump frequencies, the use of a magnetic field makes these devices bulky, heavy, and sensitive to both temperature variation and shock. Furthermore, magnetically focused electron beam devices can have different values of natural resonant frequency only by introducing additional pole pieces.

In a separate application Serial No. 289,762, filed June 21, 1963, now Patent No. 3,205,449, and assigned to the assignee of the instant application, the applicant has disclosed a novel D.C. pumped electrostatically focused electron beam parametric amplifier which has no magnetic field. The two functions of the magnetic field in the prior art devices, namely, the focusing of the electron beam and the creating of a cyclotron frequency, are accomplished by electrostatic focusing lenses. The applicant has discovered that by the use of certain ingenious structure the principles of operation of the amplifier disclosed in his application Serial No. 289,762 may be employed in D.C. pumped electrostatically focused electron beam microwave oscillator having many advantages over prior art microwave oscillators.

It is therefore an object of this invention to provide an electron beam microwave oscillator that does not require a magnetic field for focusing the electron beam or establishing a natural resonant frequency for the system.

It is another object of the invention to provide a microwave oscillator which is light in weight, rugged, stable over a wide temperature range, and easy to construct.

It is a further object of the invention to provide a D.C. pumped electrostatically focused electron beam microwave oscillator which is voltage-tunable over a broad range of frequencies.

According to the present invention, the foregoing and other objects are attained by providing an electron gun which develops a sheet electron beam, a collector longitudinally spaced from the electron gun and positioned to receive an electron sheet beam developed by the electron gun, and an electrostatically focused D.C. pump interaction structure positioned between the electron gun and the collector and having a plurality of electrostatic focusing lenses periodically spaced longitudinally along the path of a sheet electron beam developed between the electron gun and the collector, the lens strength of the electrostatic focusing lenses being above the critical value at which a sheet electron beam developed between the electron gun and the collector becomes unstable causing the sheet electron beam to have a natural frequency of transverse oscillation that increases in amplitude exponentially about a central plane extending longitudinally between the electron gun and the collector, the interaction structure being electrically divided into two regions to cause the R.F. field in the interaction structure adjacent the electron gun to be 180° out of phase with the R.F. field in the interaction structure adjacent the collector.

The specific nature of the invention, as well as other objects, aspects, uses and advantages thereof, will clearly appear from the following description and from the accompanying drawing in which:

FIG. 1 is illustrative of the D.C. pumping action employed in this invention;

FIG. 2 shows a specific embodiment of the invention wherein shorting bars are used to establish a standing wave of transverse R.F. electric field thereby providing the required 180° phase reversal;

FIG. 2a illustrates the phase reversal of the R.F. electric vector in the structure shown in FIGURE 2;

FIG. 3 shows another specific embodiment of the invention wherein the required 180° phase reversal is provided by crossing over electrostatic focusing lens connections in the interaction structure; and

FIG. 3a illustrates the phase reversal of the R.F. electric vector in the structure shown in FIGURE 3.

Referring now to the drawings and more particularly to FIGURE 1, a series of deflector plate pairs 11-11' and 12-12' are alternately and periodically spaced longitudinally along the path of a sheet electron beam, represented by the line 14. A first voltage V_1 is applied to the deflector plate pairs 12-12', and a second voltage V_2 is applied to the deflector plate pairs 11-11'. In FIGURE 1 the voltage V_1 is greater than the voltage V_2 , and the arrows between plate pairs 11-11' and 12-12' represent the electrostatic forces acting on electrons. The deflector plate pairs 11-11' and 12-12' are maintained at potentials positive with respect to the cathode of the electron gun (not shown) which produces the sheet electron beam represented by line 14. The potential difference between deflector plate pairs 11-11' and 12-12' establishes a series of convergent electrostatic lenses along the direction of electron beam travel. The electrostatic focusing lens system imparts to the electron sheet beam a time average restoring force that acts to pull the beam towards the plane of symmetry represented by the line 15. This restoring force establishes a transverse natural resonant frequency and a corresponding transverse resonant electron beam wavelength. This electron wavelength decreases with increasing lens strength. Lens strength is proportional to

$$\frac{V_1 - V_2}{V_1 + V_2}$$

When the lens strength has been increased to the point where the electron wavelength is equal to two periods D.C. voltage variation ($\lambda_e = 2L$, where L is the spacial periodicity of voltage variation), instability of the electron beam motion occurs, and the transverse displacement of the electron beam increases exponentially with distance at the expense of decreasing longitudinal velocity of the electron beam. Solutions of the paraxial-ray equation have shown that throughout this unstable region the electron wavelength remains fixed at two periods of D.C. voltage spacial variation, and that the phase of the transverse displacement of the exponentially increasing beam is such that the beam always crosses the plane of symmetry in the middle of a high potential plate pair 12-12' and has its maximum transverse displacement in the middle of a low potential plate pair 11-11'. This instability is caused by a form of parametric pumping, i.e., each electron experiences a rate of change of D.C. electric field at twice its natural resonant frequency, and has been termed "D.C. pumping" because no external R.F. pumping field is applied. By proper choice of the ratio of a/d where d is the transverse spacing between plates and a is the longitudinal periodicity of plate pairs, the desired instability condition can be achieved with the voltage V_2 made equal to the cathode or ground potential. The electron gun can be designed so that the required current is obtained with the electron gun anode operated at a voltage equal to V_1 . Thus, the oscillators according to the present invention require only one source of D.C. potential. Setting the voltage V_2 equal to zero also creates the favorable situation in which the desired condition of electron beam instability is unaffected by varying V_1 thereby facilitating tuning the oscillators. If V_2 were a voltage other than zero, tuning the oscillators would require both the voltages V_1 and V_2 to be varied simultaneously to maintain the desired condition of instability. Setting the anode voltage equal to V_1 also assures that the required current enters the structure at all times. This is most important because for an electron beam operating in the unstable region the beam thickness will increase exponentially due to instability of the electrons within the beam if the current in the structure is too high or too low. An approximate formula for the required perveance of an electron sheet

5

beam in the unstable region of an electrostatic focusing structure is

$$P = \frac{I}{V_0^{3/2}} = \frac{4.5A}{a^2}$$

5 condition of instability. Setting the anode voltage equal and V_0 is the space average voltage and is equal to

$$\frac{V_2 + V_1}{2}$$

10 The electron beam also has a tendency to spread in the lateral direction. An electrostatic field that acts to counteract the space charge spreading forces in this lateral direction can be created by curving the plates at the voltage V_1 in a convex manner and making the plates at the voltage V_2 planar. This technique of lateral focusing is described in more detail in another of the applicant's patent applications Serial No. 207,130, filed July 2, 1962, and assigned to the assignee of the instant application. Besides acting to focus the electron beam laterally, this technique also acts to counteract the tendency of the space charge depression at the center of the electron beam to create a variation of longitudinal electron velocity as a function of lateral position. This 15 mechanism of lateral focusing is of particular interest for the oscillators of the instant application where the perveance of the plate structure is kept constant because the lateral focusing force counterbalances the space charge spreading force for all values of the voltage V_1 .

20 The particular plate structure shown in FIGURE 1 is only illustrative of the structure that may be employed in the oscillators of this invention. Other and different plate structures may be used with equal effect. Exemplary of suitable plate structures are those described and 25 shown in the aforesaid application Serial No. 289,762 with particular reference to FIGURES 3, 4, 5 and 6 of the said application.

25 Reference is now made to FIGURE 2 of the drawings which shows a specific embodiment of a microwave oscillator according to the invention. Basically, the oscillator 30 comprises an electron gun 21 for producing a sheet electron beam, a collector 22 for receiving the electron beam, and an interaction structure having two regions 23 and 24 disposed between the electron gun 21 and the collector

The required phase reversal of R.F. electric field can be achieved in a structure that is substantially shorter than one quarter-wavelength long as shown in FIGURE 3. Except for the difference in length of the interaction structure, the oscillator shown in FIGURE 3 is substantially the same as the oscillator shown in FIGURE 2. Again, the intersection structure is divided into two regions 41 and 42; however, in this case the division, and the required 180° phase reversal of the R.F. electric field is achieved by crossing over the deflector plate connections. More particularly, opposing plates of a deflector plate pair at potential V_1 are cross-connected with opposing plates of the next succeeding deflector plate pair at potential V_1 , while opposing plates of a deflector plate pair at potential V_2 adjacent to the first mentioned deflector plate pair at potential V_1 are cross-connected with opposing plates of the next succeeding deflector plate pair at potential V_2 . The phase reversal of the R.F. electric field resulting from these cross-connections is illustrated in FIGURE 3a.

The operation of the oscillators shown in FIGURES 2 and 3 is the same. Electrons entering the interaction structure have a transverse motion imparted to them by the transverse R.F. electric field. As soon as the electrons have a transverse displacement, the D.C. pumping mechanism due to the condition of electron beam instability in the electrostatic focusing structure also acts on the electron beam. Thus, in the region of the interaction structure adjacent to the electron gun (region 23 in FIGURE 2 and region 41 in FIGURE 3), both the R.F. field and the D.C. pumping mechanism act to enhance the transverse displacement of the electron sheet beam causing all the electrons throughout this region to be displaced on the same side of the plane of symmetry of the interaction structure. This displacement defines an electron beam wave which oscillates back and forth across the plane of symmetry at the natural resonant frequency of the beam. When the electron beam passes from the region of the interaction structure adjacent to the electron gun to the region adjacent the collector (region 24 in FIGURE 2 and region 42 in FIGURE 3), the phase relationship between the electron beam wave and the R.F. electric field changes by 180°. As a result, transverse energy is now transferred from the electron beam to the R.F. field. In this region, the D.C. pumping mechanism continues to enhance the transverse electron beam motion, while the interaction of the electron beam with the R.F. field acts to decrease the transverse beam motion. By proper design of the device, i.e., by choosing the proper value for the focusing lens strength determined by the ratio d/a and also the proper value for the lengths of the two regions which comprise the interaction structure, the R.F. field will remove transverse beam energy as fast or faster than the beam obtains energy from the D.C. pumping mechanism thereby preventing electrons in the proper phase from impinging on the deflector plates. Most of the energy coupled onto the plates in the region of the interaction structure adjacent the collector is coupled to the R.F. output. Some of the energy is dissipated in the L-C tank circuit, and some is utilized as feedback by having the R.F. field impart a transverse motion of the proper phase to the electron beam in the region of the interaction structure adjacent the electron gun.

The output frequency of the oscillators according to this invention is equal to the natural resonant frequency of the electron beam. Since the electron beam wavelength is constant ($\lambda_e = 2L$) when the focusing structure is operating in the unstable region, the natural resonant frequency depends only on the time average velocity ($V_{av.}$) of the electron beam which is a function of the voltage V_1 . Thus,

$$f_e = \frac{V_{av.}}{\lambda_e} = \frac{5.93 \times 10^5 \sqrt{KV_1}}{2L}$$

where K is a constant proportional to the ratio of $V_{av.}/V_1$. The value of K depends on the geometry of the focusing structure and the ratio of V_2/V_1 . The upper limiting frequency of the oscillator depends on how small the deflecting plate periodicity, a , can be made and how large V_1 can be made. For example, assuming a equal to 30 mils and V_1 equal to 2,000 volts, the upper frequency of operation is about 5500 mc. It is possible to tune the oscillators according to the invention over a range of approximately 10% of a center frequency of operation by varying the deflector plate voltage V_1 . The oscillators can be made to oscillate over a wider range of frequencies simply by changing distributed inductances.

Since frequency, structure periodicity, time average velocity, and current are so closely related, the D.C. input power at a given frequency is determined uniquely by the structure periodicity a . An approximate formula for the D.C. input power is

$$\text{Power input} = 6.3 \times 10^{30} A a^3 f e^5$$

Since the beam cross-sectional area, A , can be made proportional to d , and d/a is chosen at a fixed value to make V_2 equal to zero, a is proportional to A , and the input power is proportional to a^4 . Thus, the input power can be varied over a fairly wide range. The lower value of input power is limited by either how small a can be made or the minimum current required to sustain oscillations. The upper value of the input power is limited either by how high V_1 can be made without causing inter-electrode arcing or how high large a current is available from the electron gun. For a given structure, assuming a constant efficiency and a constant permeance for the device, the output power increases strongly with increasing frequency as shown by the equation for power input.

The efficiency of the oscillators according to the invention is not high because of certain limiting factors. Depending upon the R.F. phase at which electrons are introduced into the interaction structure, some electrons undergo large transverse displacements and correspondingly large longitudinal deceleration while others experience no transverse displacement and no longitudinal deceleration. Those electrons that do not experience any longitudinal deceleration obviously play no part in transferring D.C. energy to R.F. energy and thus contribute to lowering the overall efficiency. Furthermore, those electrons that are slowed down by the D.C. pumping mechanism have their natural resonant frequency changed due to the fact that their time average longitudinal velocity has changed. Decelerated electrons will therefore fall out of the required phase for optimum interaction with the R.F. field, deleteriously affecting the efficiency. These decelerated electrons will, however, impinge on the deflector plates and be removed from the interaction region before falling more than 90° out of phase with the R.F. field thereby preventing them from reabsorbing R.F. energy. The reason for this is that the decelerated electrons give up less transverse energy to the R.F. field due to their falling out of phase with the R.F. field. In addition, they also experience a higher rate of exponential transverse displacement because the effective electrostatic lens strength increases with decreasing electron velocity. It is possible that tapering the periodicity of the plate structure may enhance efficiency in a similar manner to the improvements that have been achieved in traveling-wave tubes and backward-wave oscillators.

What have been described are D.C. pumped electrostatically focused microwave oscillators having the advantages of being voltage tunable, simple to construct, extremely rugged, lightweight since they require no magnet, and requiring only one D.C. voltage source. Obviously, many modifications and variations of the present invention are possible in view of the above teachings. It is therefore, to be understood, that within the scope of the appended claims, the invention may be practiced otherwise than as specifically described.

I claim:

1. A voltage-tunable D.C. pumped electrostatically focused electron beam microwave oscillator comprising:
  - (a) an electron gun which develops a sheet electron beam,
  - (b) a collector longitudinally spaced from said electron gun and positioned to receive a sheet electron beam developed by said electron gun, and
  - (c) an electrostatically focused D.C. pump interaction structure positioned between said electron gun and said collector and having a plurality of electrostatic focusing lenses periodically spaced longitudinally along the path of a sheet electron beam developed between said electron gun and said collector, the lens strength of said plurality of electrostatic focusing lenses being above the critical value at which a sheet electron beam developed between said electron gun and said collector becomes unstable causing the sheet electron beam to have a natural frequency of transverse oscillation that increases in amplitude exponentially about a central plane extending longitudinally between said electron gun and said collector, said interaction structure being electrically divided into two regions to cause the R.F. field in the interaction structure adjacent said electron gun to be 180° out of phase with the R.F. field in the interaction structure adjacent said collector.
2. A voltage-tunable D.C. pumped electrostatically focused electron beam microwave oscillator as defined in claim 1 wherein said electrostatic focusing lenses comprise:
  - (a) first and second series of deflector plate pairs alternately and periodically spaced longitudinally along the path of a sheet electron beam developed between said electron gun and said collector,
  - (b) a first source of positive voltage connected to said first series of deflector plate pairs, and
  - (c) a second source of voltage less than the voltage of said first source connected to said second series of deflector plate pairs.

3. A voltage-tunable D.C. pumped electrostatically focused electron beam microwave oscillator as defined in claim 2 wherein said electron gun includes a cathode and an anode and said first source of positive voltage is further connected to said anode and said second source of voltage is further connected to said cathode.
4. A voltage-tunable D.C. pumped electrostatically focused electron beam microwave oscillator as defined in claim 3 wherein said first source of positive voltage is variable.
5. A voltage-tunable D.C. pumped electrostatically focused electron beam microwave oscillator as defined in claim 2 wherein opposing plates of two pairs of adjacent deflector plate pairs near said electron gun are R.F. short circuited thereby establishing a standing wave of transverse R.F. field and thus defining the division of said interaction structure into two regions.
6. A voltage-tunable D.C. pumped electrostatically focused electron beam microwave oscillator as defined in claim 2 wherein opposing plates of a deflector plate pair of said first series are cross-connected with opposing plates of the next succeeding deflector plate pair of said first series and the opposing plates of a deflector plate pair of said second series adjacent the first mentioned deflector plate pair of said first series are cross-connected with opposing plates of the next succeeding deflector plate pair of said second series thereby reversing the phase of the transverse R.F. field and thus defining the division of said interaction structure into two regions.
